Primary Examiner — Melanie H Tung*Assistant Examiner* — Bao-Yen T Nguyen(74) *Attorney, Agent, or Firm* — Caitlyn Ross**CLAIM**

The ornamental design for a display screen with graphical user interfaces, shown and described.

DESCRIPTION

FIG. 1 is a front view of a first embodiment of a display screen with graphical user interface, showing our new design;

FIG. 2 is a front view of a second embodiment of a display screen with graphical user interface, showing our new design; and,

FIG. 3 is a front view of a third embodiment of a display screen with graphical user interface, showing our new design.

The broken lines illustrate the display screen and form no part of the claimed design. The broken lines illustrate portions of the graphical user interface and form no part of the claimed design.
